CLARENCE W. HANSELL, OF ROCKY POINT, NEW YORK, ASSIGNOR TO RADIO CORPORATION OF AMERICA, A CORPORATION OF DELAWARE

INTERLOCKING SWITCHING ARRANGEMENT

Application filed March 22, 1927. Serial No. 177,377.

This invention relates to an interlocking switching arrangement, and more particularly to such an arrangement applied to the circuits associated with electron emission tubes.

If the full operating voltage is suddenly applied to the filament of an electron emission tube of large size the results may prove disastrous, for the filament sometimes breaks because of its inability to respond to the sudden expansion requirement placed upon it. It is further stressed by reason of the abnormal magnetic forces set up, inasmuch as the initial current flow is much greater than the normal operating current because of the reduced resistance of the filament when cold. It is an object of my invention to prevent the application of the full filament potential when the filament is cold. This I do by placing in series with the operating means for closing the filament heating circuit a limiting contactor arranged to be closed by the filament rheostat only when the resistance of the rheostat is entirely cut in circuit. In this way, should the rheostat have been left cut out of circuit when the filament circuit was last opened, the operating means are made inoperative to close the circuit.

Of course, after the filament circuit is closed the rheostat is substantially cut out of circuit in order to bring the filament temperature up to its normal operating point. In such case, the limiting contactor will have opened. Nevertheless, the operating means for the filament circuit should at this time be operative in order that the filament circuit may be opened. Accordingly, it is a further object of my invention to provide operating means for the opening or closing of a circuit associated with an electron emission tube which, though inoperative for one of its functions when the filament rheostat is at one of its extreme adjustments, will, nevertheless, be operative for the other of its functions.

For reasons which will be more fully explained hereinafter it is found that the electron velocities within the tube are greater when the filament is at low than when at high temperature. This high electron ve-

locity leads to excessive plate temperature. It also results in secondary emission from the grid, which may even be damaged by the high impact velocities. High electron velocities also tend to cause ionization of any gas which may be present in the tube, with accompanying deleterious effect. To prevent these difficulties the anode potential should not be applied to the tube anode until the filament has attained substantially the normal operating temperature. It is a still further object of my invention to so interlock the filament and anode circuits of an electron emission tube that the operating means for opening or closing the anode circuit will be inoperative to close the anode circuit when the filament temperature is not within its working range.

The specification is accompanied by a drawing in which—

Figure 1 is a wiring diagram for a preferred embodiment of my invention; and

Figure 2 is explanatory of certain phenomena in electron emission tubes.

Referring to Figure 1 of the drawing, the electron emission tubes 2 have filaments 4 which are energized from a power supply line 6, which in this case has been represented as an alternating current supply, but which may, of course, be a source of direct current. In series with this supply there is a relay operated switch S_1 , and a filament rheostat R . The rheostat R comprises resistance element 8 and a control means 10 for cutting in or out more or less of the resistance 8. When all of the resistance is cut in, that is, when the control means 10 is at its lowermost position, it engages and closes the limiting contactor 12.

The control switch 14 may be considered broadly an operating means for opening or closing the power supply circuit. If the limiting contactor 12 is depressed when the operating means 14 is closed a circuit is established through the magnet 16 which attracts the armature 18, and so closes the switch S_1 . If the resistance 8 is not entirely cut in circuit then the limiting contactor 12 is open, and the operating means 14 is inoperative to close the switch S_1 . However,

once the switch has been closed, then if the rheostat control 10 is rotated to cut out part of the resistance 8, and the limiting contactor 12 opens, nevertheless the switch S_1 5 will not be opened for the reason that a circuit is established through the extra holding contact 20 which short circuits the limiting contactor 12.

By the means so far described the operating means 14 is inoperative to close the filament heating circuit when the filament rheostat is not entirely cut in circuit, or in other words, full filament potential cannot be applied to the filament when it is cold, yet the 15 operating means is always effective to open the filament heating circuit.

In electron-emission tube circuits the anode potential and the anode current are practically 180 degrees out of phase. In consequence, 20 the quantum of electron flow is least when the anode potential is greatest, and most when the anode potential is least. In actual practice an electron tube oscillator is usually so adjusted that there is no electron flow at all 25 except at the time that the grid swings most positive, which is when the alternating anode potential is most negative. For this reason whatever damage is caused by high electron velocities within the tube occurs at the instant 30 of most negative alternating anode potentials, or, when electron current is greatest. Inasmuch as the anode alternating potential exists only with reference to a constant direct potential it follows that the actual magnitude 35 of the anode potential, with reference to a true zero axis, at the time the alternating anode potential is most negative, is really highest when the amplitude of alternating potential is least. This leads to the apparently 40 unexpected result that highest electron velocities result when the anode alternating potential amplitude is least, for the velocity depends upon the actual magnitude of the attracting anode potential, for a given grid potential. This alternating potential amplitude is lower at lower filament temperature 45 because at that time there is limited electron emission.

To fix the ideas reference is made to Figure 50: 2 of the drawings, in which curve 50 represents the grid potential with reference to a "holding potential" 52. The resulting anode current at normal filament temperature, and a lesser current for lower filament temperatures, are shown by curves 54 and 56 respectively. The steady anode potential is 58; the normal anode alternating potential, accompanying anode current 54, is represented by curve 64; and the smaller amplitude alternating anode potential, accompanying anode current 56, is represented by curve 66. The 55 actual anode potential, at the time of electron flow, is normally x ; but with lower filament temperatures, is the greater value y .

60 It is therefore exceedingly desirable to

prevent the anode circuit from being closed before the filament temperature has been brought to its ordinary working range.

Again referring to Figure 1 of the drawing, the direct current supply for the anode cathode circuit is obtained from a rectifier 26, to which an alternating current supply is led by way of the conductors 28. In this alternating current supply there is inserted a switch S_2 . Of course, a direct current supply other than a rectifier may be employed, and in some cases it might prove preferable to locate the anode switch S_2 in the direct current leads themselves. This switch S_2 , like S_1 , is relay operated by means of a magnet 30 and an operating switch 32, which closes the relay magnet circuit.

To prevent its being closed while the filament is cold the anode switch is interlocked by the use of another limiting contactor 34, so located, as shown, that the rheostat control 10 must substantially cut out the resistance 8 before the limiting contactor 34 is closed.

The filament rheostat R may be used as a filament temperature control as well as a starting resistance, for the reason that the control 10 may be backed away from the contactor 34 once the switch S_2 has been closed. This is accomplished by employing a holding contact 36, which short circuits the contactor 34.

Although the holding contacts 20 and 36 on switches S_1 and S_2 short circuit the contactors 12 and 34, nevertheless they do not make inoperative the operating switches 14 and 32, for these are in series with the holding contacts, and therefore are operative to open the respective relay circuits of the switches S_1 and S_2 .

The foregoing is by way of illustration and not limitation of my invention, which I claim is:

1. In combination, an electron emission tube, a starting rheostat for gradually building up the filament heating current therefor, a circuit associated with said tube, operating means for opening or closing said circuit, and means to make said operating means inoperative for one of its functions when said starting rheostat is set near one of its extremes of adjustment even though not open circuited.

2. In combination, an electron emission tube having an electron emitting cathode, a source of potential associated with the terminals of said cathode, a starting rheostat for gradually building up the potential applied to the terminals of said cathode, relay controlled operating means for opening or closing a circuit between said source and cathode, and means to make a relay circuit of said operating means inoperative for one of its functions when said starting rheostat

is set near one of its extremities of adjustment.

3. In combination, an electron emission tube, a filament heating circuit including a source of filament heating current, a starting rheostat for gradually building up the magnitude of said current, operating means for opening or closing the circuit, and means to make said operating means inoperative to close said circuit when the resistance of the starting rheostat is partially and not fully in circuit.

4. In combination, an electron emission tube, a filament heating circuit including a source of filament heating current, a starting rheostat for gradually building up the magnitude of said current, operating means for opening or closing the circuit, and means to make said operating means always operative to open said circuit but inoperative to close said circuit when the resistance of the starting rheostat is partially and not fully in circuit.

5. In combination, an electron emission tube, a cathode heating circuit therefor including controlling means to control the cathode temperature, an anode circuit including operating means to open and close said anode circuit, and means, responsive to the cathode temperature controlling means, for rendering the operating means inoperative to close the anode circuit until the filament temperature has been brought substantially to its normal working temperature.

35 6. In combination, an electron emission tube, a cathode heating circuit including controlling means to control the cathode temperature, an anode circuit including operating means to open and close said anode circuit, and means, responsive to the cathode temperature controlling means for rendering the operating means operative to open the anode circuit and inoperative to close said circuit until the cathode temperature has 45 been brought substantially to its normal working temperature.

7. In combination, an electron emission tube, a filament heating circuit including a rheostat for controlling the heating current, an anode circuit, a source of anode current, operating means to connect and disconnect said source and said anode circuit, and means to make the operating means inoperative to connect the source and the anode circuit 55 when the filament rheostat is not substantially cut out of circuit.

8. An interlocking switching arrangement for an electron emission tube and its associated cathode and anode circuits comprising operating means to open and close said circuits, a starting rheostat in the cathode circuit, means for rendering operative said cathode operating means upon substantial inclusion of the rheostat resistance in circuit thereby preventing sudden heating of

the cathode, and, means responsive to the movement of said rheostat for rendering operative said anode operating means upon removal of the rheostat resistance from the cathode circuit.

9. In combination, an electron emission tube having a heated cathode, a heating circuit including a starting rheostat for gradually applying the heating current, a relay operated switch for opening and closing the heating circuit, operating means for the relay, and means to make the operating means inoperative to close the switch when the resistance of the starting rheostat is not fully in circuit.

10. In combination, an electron emission tube having an anode and a heated cathode, a heating circuit including a starting rheostat for gradually applying the heating current, an anode circuit, a source of anode current, a relay operated switch for connecting and disconnecting said source and said anode circuit, operating means for the relay, and means to make the operating means inoperative to close the switch when the starting rheostat is not substantially cut out of circuit.

11. An interlocking switching arrangement comprising an electron emission tube having an anode and a heated cathode, a heating circuit including a starting rheostat for gradually applying the heating current, a first relay operated switch for opening and closing the heating circuit, an anode circuit, a source of anode current, a second relay operated switch for connecting and disconnecting said source and said anode circuit, operating means for the relays, and means to make the operating means inoperative to close the first switch when the resistance of the rheostat is not fully in circuit, and inoperative to close the second switch when the rheostat is not substantially cut out of circuit.

12. In combination, an electron emission tube, means for gradually building up the cathode heating current therefor, a circuit associated with the tube, operating means for opening or closing said circuit, and means to make said operating means inoperative for one of its functions when said current building up means is set near one of its extremes of adjustment even though not open circuited.
